FRANCIS L. ORR AND OTTO H. JAHNKE, OF DENVER, COLORADO.

WATER ELEVATOR.

1,413,930.

Specification of Letters Patent. Patented Apr. 25, 1922.

Application filed July 31, 1920. Serial No. 400,452.

To all whom it may concern:

Be it known that we, FRANCIS L. ORR and OTTO H. JAHNKE, citizens of the United States, residing at Denver, in the county of Denver and State of Colorado, have invented certain new and useful Improvements in Water Elevators; of which the following is a specification.

Our invention relates to improvements in water elevators of the type in which a series of buckets pivotally mounted on an endless carrier pass successfullly through a body of water and discharge their contents into a receptacle above the surface thereof.

15 The present improvements are particularly adapted for use on water elevators in which buckets pivotally mounted on a pair of endless chains, carry stops which by engagement with the chains limit their pivotal movement in order to place them in the proper position to receive and discharge the liquid through which they pass.

It is the primary object of the present invention to provide in connection with the 25 pivoted buckets of an elevator of this character, a novel construction and arrangement of the stops above referred to and another object is to provide an adjustment for the stops, whereby the pivotal movement of the 30 buckets on the carrier may be modified in order to maintain a maximum efficiency under different conditions.

With the above and other objects in view all of which will fully appear in the course 35 of the following description, our invention resides in the construction and arrangement of parts shown in the accompanying drawings in the various views of which like parts are similarly designated and in which—

40 Figure 1 is a side elevation of my improved water elevator partially in section;

Figure 2, a front elevation of the same looking in the direction of the arrow A, Figure 1;

45 Figure 3, a side elevation of one of the buckets of the device;

Figure 4, a section taken on the line 4—4, Figure 3; and

50 Figure 5, a cross section through one of the buckets showing the arrangement of the adjustment for the stop pin at the inside of an end thereof.

Referring more specifically to the drawings, the reference numeral 5 designates a 55 structure of suitable construction and proportions which supports the operating parts

of the mechanism above a body of water to be raised.

Boxes 6 secured at the top of the structure in horizontal axial alinement support a 60 shaft 7 which at one of its ends is operatively connected with a driving and controlling mechanism which includes a driving pulley 8 and a hand-controlled appliance 9 to make or break the rotative continuity of 65 the shaft and the pulley while the latter is in motion.

Mounted upon the shaft in spaced relation to each other are a pair of sprocket wheels 25 over which are trained the endless chains 70 26 which conjointly constitute the carrier for the buckets of the elevator.

A pair of sprocket wheels 27 at the ends of a connecting shaft 28 engage the chains 75 at their lower ends to keep them in a taut condition and at the required distance from each other.

The buckets 29 which are loosely fitted between the chains are pivotally connected with corresponding links thereof by means 80 of pins 30 which in the present construction are formed in integral connection with the stop pin 31 which determine the position of the buckets with relation to the chains in the operation of the elevator, as will hereinafter be more fully described.

The two pins are provided by the parallel arms of a U-shaped piece 32 which are threaded at their extremities for the application of nuts 33 and 34.

90 Each bracket has in its ends apertures in the plane of its longitudinal axis to receive the arms of the U-shaped pieces which constitute the pivot pins by which the bucket is connected to the chains and it has furthermore in concentric relation to said apertures, arcuate slots 35 through which extend the other arms of the pieces 32 representing the stop pins 31 of the construction.

Collars 39 formed on the pins engage the 100 end plates of the buckets at the external sides of the bucket and an apertured plate 36 placed upon the threaded ends of the pins at the opposite side of the plate perform the function of a washer and covers the respective slot 35 to prevent the outflow of water.

The pivot pins extend loosely through apertured lugs 37 of the links of the chains between which the buckets are connected and 110 the stop pin extends exteriorly of the endless chains to engage the same when in the

movement of the elevator the buckets turn limit the extent of their pivotal movement about their axes of the shafts on which the by engagement with said carrier. chains are mounted.

It will be apparent that the nuts 33 and 34 normally clamp the stop pins in their adjusted position with relation to the vertical plane of the axis of the respective buckets, and that by loosening the nuts the pins may be moved in the arcuate slots through which 10 they extend for the purpose of changing their distance from said plane.

In the operation of the water elevator, the upper shaft being slowly rotated through the medium of the driving mechanism hereinbefore described, imparts its movement to the sprocket wheels from which the endless chains are suspended.

The movement of the chains in the direction of the arrow B, Figure 1, causes the 20 buckets to successfully enter the body of water above which the supporting structure is erected and whose level is indicated in the drawings by a broken line C.

The buckets pass around the sprocket 25 wheels in a position which is determined by the engagement of the stop pins with the chains and while moving downwardly toward the water level they gradually turn about their pivots and enter the water in 30 a partially inverted position.

The pressure of the water causes a quantity of air to be entrapped in the buckets with the result that they remain in an inverted position while passing around the sprocket 35 wheels on the lower shaft and are gradually rotated on the upwardly moving side of the chains to leave the water in their normal upright position.

The water with which the buckets were 40 filled during their passage through the body of water is carried over the upper sprocket wheels and discharged into a chute 38 at the downwardly moving side of the elevator.

By proper adjustment of the stop pins the 45 movement of the buckets about their pivotal axes may be regulated so that the water is lifted with the minimum expenditure of motive energy and so that the buckets assume their different positions without violent impact with the chains on which they are carried.

It will be observed that the lower pair of sprocket wheels are not mounted for rotation about a fixed axis, as in other constructions of this type but act merely as a means 55 to maintain the chains in a taut condition and facilitate the movement of the buckets through the body of water to be lifted.

Having thus described our invention what 60 we claim and desire to secure by Letters-Patent is:

1. In a water elevator of the character described, the combination with an endless carrier, and buckets pivotally mounted thereon, 65 of adjustable stop pins on the buckets, which

limit the extent of their pivotal movement by engagement with said carrier. 2. In a water elevator of the character described, the combination with an endless carrier and buckets pivotally mounted thereon, 70 of stop pins which limit the extent of the pivotal movement of the buckets by engagement with the carrier, said pins being mounted at the ends of the buckets for adjustment to selected distances from the vertical planes 75 of the pivotal axes of the same.

3. In a water elevator of the character described, the combination with an endless carrier, of buckets pivotally mounted thereon and having at their ends slots concentric 80 with their pivotal axes, and stop pins adjustably fastened in said slots and adapted to limit the extent of the pivotal movement of the buckets by engagement with the carrier.

4. In a water elevator of the character described, the combination with an endless carrier, of buckets having in their end-plates apertures for their pivotal connection with the carrier, and slots concentric with said apertures, substantially U-shaped pieces providing in integral connection with each other, pivot pins extending through said apertures in connection with the carrier, and stop pins extending through said slots, and means for securing the stop pins in their 95 adjusted positions.

5. In a water elevator of the character described, the combination with an endless carrier, of buckets having in their end-plates apertures for their pivotal connection with the carrier, and slots concentric with said apertures, substantially U-shaped pieces providing in integral connection with each other, pivot pins extending through said apertures in connection with the carrier, and stop pins extending through said slots, said pins being threaded for the application of nuts and having collars engaging the external surfaces of the end plates, and nuts 100 screwed upon the ends of the pins and co-operating with said collars to secure the stop pins in their adjusted positions.

6. In a water elevator of the character described, the combination with an endless carrier, of buckets having in their end-plates 115 apertures for their pivotal connection with the carrier, and slots concentric with said apertures, substantially U-shaped pieces providing in integral connection with each other, pivot pins extending through said apertures in connection with the carrier, and stop pins extending through said slots, said pins being threaded for the application of nuts and having collars engaging the external surfaces of the end plates, washers on 120 the pins engaging the opposite sides of the plates and covering the slots, and nuts on the pins screwed against said washers to secure the stop pins in their adjusted positions.

7. In a water elevator of the character described, the combination with an endless carrier and buckets pivotally mounted thereon, of U-shaped pieces extending from the ends 5 of the buckets and providing in integral connection with each other, pins for the pivotal connection of the buckets with the

carrier and stop pins which limit the pivotal movement of the buckets by engagement with the carrier.

In testimony whereof we have affixed our signatures.

FRANCIS L. ORR.
OTTO H. JAHNKE.
